UNITED STATES PATENT OFFICE.

CARLETON B. GIBSON, JR., OF SAVANNAH, GEORGIA.

DRILL BIT.

Application filed October 10, 1921. Serial No. 506,817.

To all whom it may concern:

Be it known that I, CARLETON B. GIBSON, Jr., a citizen of the United States, and resident of Savannah, in the county of Chatham 5 and State of Georgia, have invented certain new and useful Improvements in Drill Bits, of which the following is a specification.

My present invention relates to improvements in drill bits of the rotary type such 10 as are used in boring or sinking holes or wells in search of underground water, oil, gas or other substances.

This invention aims to provide a drilling tool of extremely simple, economical and effective design which, while retaining all the good features which have caused the fish-tail bit to be generally adopted, will obviate the great expense and loss of time necessary for renewing the cutting blades of the drill 20 bit by providing a drill bit which may readily be inserted into and removed from the hole and the cutting blades of which may be quickly and easily removed and renewed without withdrawing the drill stem or well 25 casing, which acts as the drill rotating shaft, from the hole.

A further object is to provide an improved drill bit of the type above described which is of the simplest and most durable 30 construction and which may be economically manufactured.

A still further object of the invention is to eliminate the use of a special drill pipe or stem and save the cost of obtaining and 35 handling such drill pipe by providing a tool which may be operated by the well casing which is to remain permanently in the hole drilled.

A still further object of the invention is 40 to eliminate the necessity of procuring, carrying on hand, and installing several different sizes of well casing in any one well, as is now done, by providing a tool which may be operated by the permanent well casing, which will permit of this casing following the drill bit down into the hole as it is made, and which will permit of removing and renewing the cutting blades without disturbing the well casing or materially lowering 45 the mud used to keep gas or water from the surrounding earth from entering the hole. This is of the greatest importance in sinking wells in country where strong gas or water pressure is encountered.

50 A still further object of the invention is

to obviate the necessity of tool joints such as are now used to connect the drill bit to the drill stem.

A still further object of the invention is to provide a collapsible drill bit which may 60 be lowered through the hollow driving shaft to the predetermined working position and to provide means for there expanding the cutting blades to the proper cutting position and locking them in such a manner that 65 they can only be contracted or closed by voluntarily withdrawing the blade holder in the predetermined manner.

A still further object of the invention is to remove the possibility of dropping tools 70 or pipe into the hole by providing a tool the use of which minimizes the use of small tools about the mouth of the hole and the handling of short lengths of pipe into and out of the hole.

A still further object of this invention is to minimize the causes of accidents and increase the safety of operatives by reducing the number of heavy hoists and consequent strain on the derrick and obviating the necessity of having an operative working high up in the derrick whenever a bit is changed.

A still further object of the invention is to provide a tool which, when the blades and blade carrying device have been withdrawn, 80 will leave a smooth unobstructed passage throughout the well casing from bottom to top of hole.

A still further object of this invention is to provide means for conducting water from 90 the top of hole to cutting blades for the removal of cuttings.

A still further object is to provide a drill bit which will automatically clean itself of mud which might clog the mechanism.

With these and other objects in view, the invention includes the novel features of construction and arrangement and combination of parts hereinafter described and particularly defined by the appended claims.

An embodiment of my invention is illustrated in the accompanying drawings in which—

Fig. 1 is a longitudinal elevation, partly in section, of the complete tool, showing position of plunger, blades, and locking bolt when blades are expanded in the working position.

Fig. 2 is a similar elevation, partly in section, showing the plunger raised sufficiently

75

105

110

to close the blades, the locking bolt withdrawn, and the blades in the closed position ready for withdrawal.

Fig. 3 is a similar elevation, partly in section, at right angles to Fig. 1, showing the plunger down and blades expanded and locked in the working position.

Figs. 4 and 5 are longitudinal vertical sections of the barrel, taken at right angles to each other, showing the casing connection 1^a, helical guiding ramp 1^b, blade stops 1^d, and blade rotating slot 1^f.

Fig. 6 is a view of the top of the barrel looking down on it from a point above and 15 on the axis thereof.

Fig. 7 is a section through the barrel near its lower end taken on line 7—7.

Figs. 8 and 9 are elevations, partly in section, of the plunger, at right angles to each other, showing the lifting and lowering rod 2^e, the blade locking bolt 4, the plunger guides 2^f, and the blade actuating slots or grooves, 2^a.

Fig. 10 is a section through the upper portion of plunger at guides along a plane perpendicular to its axis, and showing the plunger guides 2^f and the water courses 2^x.

Fig. 11 is a section through the lower forked portion of the plunger and perpendicular to its axis, showing the blade actuating grooves 2^a and the water courses 2^x.

Figs. 12, 12^a and 12^b are detail views of the cutting blade showing also the blade actuating key or land 3^a, the blade stop 3^b, the locking bolt notch 3^c, and the barrel stop notch, 3^f.

Referring to the drawings, wherein similar reference characters designate corresponding parts throughout, the numeral 1 designates the barrel which is preferably provided with a threaded portion 1^a for attaching it to the lower end of the hollow rotating shaft formed by the drill stem or well casing, a pair of curved inclined planes 45 or helical ramps 1^b for guiding the plunger and blades into their proper positions, key ways 1^c for receiving the blade guides 3^b and the plunger guides 2^f, stops 1^d, for arresting the further descent of the blades 3, 50 and slots 1^f for holding the expanded blades in position for rotating.

Numeral 2 designates the plunger which is preferably formed from a single cylindrical piece of steel and is provided with proper recesses for the raising and lowering bar 2^e and the blade locking bolt 4, plunger guides 2^f, water courses 2^x, and a lower slotted or forked portion in the inside faces of which are cut the curved blade actuating 60 grooves 2^a of the proper curvature for expanding the blades through a predetermined angle when the plunger is moved through a certain predetermined distance along its axis.

Numeral 3 designates either one of the

two reversible interchangeable blades which are preferably formed by drop forging from one piece of steel and are provided with a curved key 3^a of the same curvature as the corresponding groove 2^a of the plunger, a blade guide 3^b and stop 3^c, a locking bolt notch 3^c, a barrel slot stop 3^f, and a cutting edge 3^x. The numeral 4 designates the blade locking bolt which is preferably formed of one piece with the hoisting bar 2^e and which, 70 with the key ways 2^a and the stop 1^d, serves to lock the blades in their expanded position and to carry the weight of the plunger and blades when lowered into or hoisted out of the hole. The hoisting bar 2^e is provided 75 with enlarged cone shaped portions 2^d and 2^e which respectively engage the hoisting tongs, not shown, while the plunger and blades are being lowered into or withdrawn 80 from the hole.

The operation of the tool is as follows:

The barrel, having been properly connected to the lower end of the drill stem or well casing, whichever may be used for the rotating shaft, is lowered into the hole until its lower end rests at a distance of about 8 inches from the bottom of the hole. The plunger is then suspended in a vertical position adjacent the mouth of the hole and the two blades are inserted, one from either side, 90 the curved blade keys entering the corresponding actuating key ways at 2^b. The blades readily drop into the closed position, the keys 3^a following the key ways 2^a until the lower end of each key brings up against 100 the lower end of the corresponding key way at 2^b; when the plunger and blades are in the relative positions shown in Fig. 2. The plunger, carrying the blades in this position, is then entered and lowered into the 105 hole, descending without interference until the blade stops 3^c or the lower extremities of the plunger guides 2^f come into contact with the curved inclined planes 1^b, when the weight of the descending plunger and 110 blades acting on the inclined planes causes the plunger to rotate until the guides will enter the corresponding straight key ways 1^c. The blade guides 3^b follow the corresponding key ways 1^c until the ends of the 115 guides 3^b are brought to a stop by the ends of the corresponding key ways 1^c at 1^d where further downward movement of the blades with respect to the barrel is arrested. The weight of the plunger causes it to continue 120 its descent, the action of the curved plunger key ways on the corresponding blade keys causing the blades to expand as the plunger descends until all further movement of the plunger blades is arrested by the 125 blade notches 3^f coming to rest against the barrel slot stops 1^d. The weight of the blade locking bolt 4 and the hoisting rod 2^e cause them to continue to descend until the lower extremity of the locking bolt comes to rest 130

against the locking bolt notches 3^c of the expanded blades. This descending movement of the hoisting bar with respect to the plunger causes the jaws of the hoisting tongs, not shown, to be opened by coming in contact with the conical surface 2¹, when the tongs may be withdrawn, the regular swivel joint connected, the pumps and rotary started up and drilling continued. It will be noted that when the tool is in the working position the blades can not be moved by either upward or lateral pressure.

In order to remove the plunger and blades for renewing the blades when their cutting edges are dulled or for any other reason, the hole is opened by removing the swivel joint and the hoisting tongs lowered by a small cable and attached to the upper cone 2^b. Pulling up on this line will then first withdraw the locking bolt which will in turn raise the plunger causing it to move upward in relation to the fixed barrel, the upward movement of the curved plunger grooves acting on the curved blade keys, contracting the blades until they are again in the position shown in Fig. 2 when the plunger and blades may be readily withdrawn from the hole. By lowering the plunger vertically to the ground adjacent the mouth of the hole, the blades will be forced upward until their upper extremities project from the sides of the plunger at 2^b when they may be readily withdrawn by hand and replaced with two new blades.

Having described my invention, what I claim is:

1. In a boring or drilling device, a barrel, a plunger cooperating therewith having inclined blade guides, blades having ribs or keys slidably engaging said guides and means carried by the barrel for arresting the descent of the blades.

2. In a device of the character described, a barrel, a plunger cooperating therewith, having inclined blade guides open at their upper ends and closed at their lower ends, blades removably seated in said guides, and means carried by the barrel for arresting the descent of the blades.

3. In a device of the character described, a barrel, a plunger for cooperating therewith and having a forked portion, the inner faces of said forks having inclined blade

guides, blades having ribs engaging said blade guides, and means carried by the barrel for arresting the descent of the blades.

4. In a device of the character described, a barrel, a plunger for cooperating therewith having a forked lower portion, provided with blade guides, a pair of juxtaposed blades between the arms of said forked portion and having ribs engaging said guides, and means carried by the barrel for arresting the descent of the blades.

5. In a device of the character described, a barrel or casing shoe, having blade engaging recesses, a plunger, telescoping blades carried by said plunger, means for positioning the plunger in said barrel to insure alignment of the blades with said recesses, and means for projecting the blades into engagement with said recesses.

6. In a device of the character described, a barrel or casing shoe, a plunger, having a cylindrical upper portion provided with a water passage, and a divided lower portion, blades slidably carried by said lower portion, and means whereby movement of the plunger in said casing spreads and retracts said blades.

7. In a device of the character described, a barrel or casing shoe, having longitudinal grooves closed at their lower ends and inclined guides cooperating with the upper ends, a plunger, and elongated blades slidably carried by said plunger and having projecting portions to cooperate with said grooves.

8. In a device of the character described, a barrel or casing shoe, having longitudinal grooves closed at their lower ends and inclined guides cooperating with the upper ends, a plunger having projections cooperating with said guides and grooves, and blades slidably carried by said plunger and having inclined guide connections with said plunger, and having projections cooperating with said casing grooves.

9. A drilling or boring device, embodying a carrying member provided with guides, and blades having portions adapted to be slid into said guides from the upper end and held therein by gravity alone.

In testimony whereof, I affix my signature.

CARLETON B. GIBSON, JR.
